LINTEL

Clarke F. Davis, Short Hills, N. J., assignor to
 American Cyanamid & Chemical Corporation,
 New York, N. Y., a corporation of Delaware

Application September 24, 1935, Serial No. 41,861

5 Claims. (Cl. 72—0.5)

The present application is a continuation of co-pending application No. 655,591.

The present invention relates to a building construction where the walls thereof are made of 5 individual units and the invention is particularly concerned with the arrangement of that construction above a door or window and means to support the units occurring there.

The above entitled application discloses a house 10 or other building where the vertical walls are composed of units such as precast slabs with their adjacent edges interlocked together by means of metal edge members bonded to the edges of the units. In such a construction, where 15 an individual unit is of less height than the distance between floor and ceiling, this difference in height may be pieced out by means of parts of other units or slabs supported directly by the first mentioned. The problem, however, of sup- 20 porting such short sections over a door or window space is a difficult one, particularly as it is desirable to have such a wall complete before the window or door bucks are put in place and, hence, without them, there would be no support 25 for such slabs otherwise.

To this end, the invention contemplates a definite support for the slabs or units over the window or door openings where such support is tied in to slabs or portions of slabs remote from such 30 opening. This supporting means may consist of a plate having an extended body with angular ends each of which is provided with a groove adapted to be clipped or fitted between the corresponding tongued and grooved adjacent edges 35 of two slabs. Where desired, these ends may be additionally nailed to the slab edges where frictional contact alone is not sufficient to prevent movement. Intermediate the ends of this sup- 40 porting plate is an angular shelf or step at right angles to the main body of the plate which is adapted to underlie and support the slab or slabs directly over the window or door opening.

The invention further consists in the novel arrangement, combination and construction of 45 parts more fully hereinafter described and shown in the accompanying drawing.

In the drawing—

Fig. 1 is a partial perspective view of a wall showing an embodiment of the invention;

50 Fig. 2 is a view along the line 2—2 of Fig. 1;

Fig. 3 is a perspective view of the supporting plate or bridging piece of Fig. 1.

Referring now with particularity to the embodiment illustrated, I have shown in Fig. 1 a wall which consists of a series of slabs having

a body portion 1 of gypsum or the like, the longitudinal edges of which are provided with complementary metal members 2 and 3 having mating tongues and grooves so that when erected, the adjacent slabs are interlocked together in a 5 tight frictional joint.

In a house where such a wall exists, it is preferable for the sake of speed and ease of erection to erect the walls solidly without regard as to where these openings may occur. After the wall 10 has been put in place, the window or door openings may then be marked out and such opening cut therefrom by hand or power. Inasmuch as the set cementitious material of which the slabs are made may be readily cut and the gauge of 15 the metal on the slab edges may be comparatively light, this severing or cutting out of the openings can be accomplished without difficulty. One such opening is indicated in Fig. 1.

After cutting this opening, the slabs A and B 20 being only partially severed, their upper portion will be supported by the lower uncut portion. The slab C, however, being completely cut off on the bottom, must rely for its support upon the frictional joint of the metal edge interlock between it and its neighboring slabs A and B. 25

In order, therefore, to adequately support this short slab C or a plurality of such slabs C, should the opening be of such width, a supporting plate or bridging piece is provided, having an extended body 4 with angular ends 5, each of which is provided with a grooved portion 6. The ends 5 are adapted to be pinched or clipped between the interlocked metal edges of two slabs as, for instance, slabs A and D and slabs B and E. 30 Where the frictional joint is not tight enough to prevent slippage of the plate 4, nails 7 may be used to additionally secure the part in place. 35

Intermediate the ends of this tie or bridging piece 4 is an angular shelf or step 8 adapted to 40 underlie the short piece of slab C. The step 8 may be of any desired extent and, as shown in Fig. 1, it extends under the cut portions of the slabs A and B likewise to lend whatever support is necessary at those points. 45

In this way, there can be no accidental displacement of the cut slab C nor is the support thereof dependent upon the use of door or window bucks. Likewise, the use of the supporting plate or bridging piece does not in any way interfere 50 with the use of such bucks.

While the invention has been shown and described with particular reference to specific embodiments, yet obviously it is not to be limited 55

thereto but is to be construed broadly and restricted only by the scope of the claims.

I claim:

1. A building construction comprising a vertical wall of precast slabs having an engaging vertical surface, an opening in said wall of a width greater than one wall slab, a slab supporting plate defining the top of said opening, said plate being secured at each end between the vertical joint 10 between wall slabs, and a wall slab supported on said plate.
2. A building construction comprising a wall of vertically arranged interlocking precast slabs, an opening in said wall, a slab supporting plate defining the top of said opening, said plate having its sides extending between and conforming to the interlock between the wall slabs, said plate having a horizontal portion between its ends, and a slab supported on said horizontal portion.

3. A building construction comprising a series of interlocking precast slabs arranged in a plane, an opening in said plane, a slab supporting plate spanning more than one slab and having its ends extending between and conforming to the interlock between the slabs. 5

4. A building construction comprising a wall of vertically arranged interlocking precast slabs, an opening in said wall, a slab supporting plate defining the top of said opening, said plate having a portion extending between and conforming to the interlock between the wall slabs, said plate having a horizontal portion between its ends, and a slab supported on said horizontal portion. 10

5. The building construction of claim 4 in which the horizontal portion of the plate is coextensive with the width of the opening. 15
